UNITED STATES PATENT OFFICE.

ERNEST R. SWANSON, OF CRANSTON, RHODE ISLAND, ASSIGNOR TO UNIVERSAL WINDING COMPANY, OF BOSTON, MASSACHUSETTS, A CORPORATION OF MASSACHUSETTS.

WINDING MACHINE.

Application filed August 3, 1926. Serial No. 126,897.

This invention relates to winding machines and particularly to drum- or friction-winders in which the yarn-cop or cone is driven by frictional contact with a rotating drive-roll or drum.

One object of the invention is to provide an improved machine of the type specified in which the winding-spindle or cop-holder moves away from the drive-roll in a certain predetermined path and is tilted in angular relation thereto, during the winding of a conical cop or package, whereby to build the cone with a gradually increasing taper on its periphery and with concavo-convex ends.

Further objects of the invention are to simplify the construction of the machine, to render its mechanism more compact, and generally to increase its efficiency while making it more convenient of operation.

A preferred embodiment of the invention is described in the following specification and illustrated in the accompanying drawings by way of example only. In the drawings:

Fig. 1 is a side elevation of a portion of the improved winding machine showing the winding-spindle or cone-holder, the drive-roll therefor, and the general arrangement of the cone-builder motion;

Fig. 2 is a plan view of the cone-holder arm;

Fig. 3 is a front view of a portion of the machine showing the cone-holder, its drive-roll and the traversing-means for the thread-guide which lays the yarn or thread on the cone, the parts being illustrated in position at the commencement of the winding;

Fig. 4 is a similar view showing the cone-holder in position removed from the drive-roll at or near the completion of winding the cone; and

Fig. 5 is a detailed view of the dogging-mechanism which acts to hold the cone-holder in raised position.

The improved machine is usually constructed in gang form with a plurality of winding units arranged in series along a suitable frame or bed. In the present drawings the frame of the machine is illustrated merely in fragmentary view, and only the essential operating-elements of a single winding-unit are shown.

Referring particularly to Fig. 1, the refer-

ence-character 2 designates a horizontal girt or frame-member which provides support for the various bearings for the longitudinal drive-shafts of the machine. A suitable number of these frame-members or girts 2 are arranged at intervals along the main frame or standard of the machine and the drive-shafts extend horizontally at right-angles with respect thereto. The frame-members 2 carry bearings 3 for a cam-shaft 4 on which is mounted a cylindrical cam 5. As shown more particularly in Fig. 3, the cam 5 has one or more helical cam grooves 6 and 7 for engaging a stud or roller 8 which travels therein. The roller 8 is connected to a thread-guide 10 which slides on a horizontal track or rod 11, and as the cam 5 is rotated from its shaft 4 the guide is reciprocated therefrom to traverse the yarn on the cop or cone. Usually, a separate cam is provided for each winding unit, but in other cases one cam may be employed to reciprocate a series of thread-guides carried on a slidable rod or bar.

Journaled in bearings 12 above the cam-shaft 4 is a second shaft 13 which carries the drive-rolls 15 arranged in series therealong, one for each winding unit. The thread-guide 10 reaches up above the drive-roll 15 and is provided with a slot or groove 16 through which the yarn γ leads to direct it on to the cop- or cone-holder 20. The cop- or cone-holder 20 is constituted in a suitably shaped mandrel which is rotatable on a dead-spindle 21 and adapted to carry a paper cop-tube or other yarn-receiver. The spindle 21 is hinged between the sides of a forked bearing-member 22 and has a notch 23 in its butt-end which is engaged by a projection 24 on a flat spring 25, see Fig. 2. The spring 25 is secured at 26 to the side of the forked bearing-member 22. The spring 25 thus holds the spindle 21 normally extending at right angles to the bearing-member 22 to support the cone-holder 20 with its axis in the vertical plane of the axis of the drive-roll 15. The bearing-member 22 is provided with upwardly extending arms 27 formed with hubs 28 which are bored to receive a stud 29 projecting forwardly from an elbow-shaped arm 30. The hubs 28 thus serve to rockably support the bearing-member 22 from the arm 30 and a

split collar 31 is clamped around the stud 29 between the hubs to hold the member in place thereon.

The arm 30 constitutes the main support 5 and lifter-means for the cone-holder 20, being hinged or pivoted to swing upwardly during the building of the cop or cone. The arm 30 is formed with spaced bearing-hubs 32, 33, see Fig. 2, which straddle the sides 10 of a forked bracket 34 supported from the cross-girt or frame-member 2. A horizontal rod or shaft 35 is held fixedly in the top of the forked bracket 34 and projects through suitable bores in the hubs 32, 33 of 15 the arm 30 to pivotally support the latter therefrom. A collar 36 secured to the end of the rod 35 abuts the bearing-hub 33 of the arm 30 to hold the arm in place on its pivot.

20 Between the hub 32 of the arm 30 and the opposite side of the bracket 34 is a loosely mounted hub 37 carrying an arm 38 which pivots on the rod 35. The arm 38 carries an arcuate, grooved guiding-track 40 at its 25 outer end which serves as the prime means for controlling the tilting action of the cone-holder 20 as it rises with its support or arm 30. The arm 38 has an arcuate slot 41 in its side, through which extends a bolt 42 adapted to tighten the arm against a vertical support or standard 43 forming a part 30 of the bracket 34, see Figs. 1 and 2. Through this means the arm 38 is adjustable on the rod 35 as a pivot to raise or lower the guiding-track 40 at its forward end. Referring 35 particularly to Fig. 4, the groove 45 in the front of the track 40 is inclined at an angle to the vertical and an arm 46 reaches downwardly from the bearing-member 22 with 40 a stud or roller 47 at its end engaging the groove. The inclined groove or guideway 45 is in effect a cam adapted to act on the follower roller 47 of the arm 46 to rock the bearing-member 22 on its pivot to tilt the 45 cone-holder 20 as the latter moves upwardly, this action being hereinafter more fully explained.

The cone-lifter arm 30 swings upwardly 50 with the cone-holder 20 during the increase in diameter of the winding and suitable means are provided to prevent a retrogressive movement thereof. Any preferred construction of dogging-mechanism may be employed for this purpose and Fig. 5 illustrates a preferred form of construction 55 thereof. Referring to this view and Fig. 1, an arcuate member or sector 50 is fixedly attached to the side of the arm 30 and extends downwardly in substantially concentric relation with the pivotal axis of said arm. The sector 50 may be attached to the arm 30 in any suitable manner and, as shown in 60 Fig. 2, is inserted in a slot 51 in the side of the arm and clamped in place by a bolt 52 and washer 53. The sector 50 is provided

with ratchet-teeth 55 on its rearward side which are engaged by a pawl 56 pivoted to an arm 57. The arm 57 projects from a bearing 58 which is fixedly secured to a cross-rod 59 forming a part of, or suitably supported from, the main frame of the machine. The pawl 56 is held in engagement with the teeth 55 of the ratchet by means of a plunger-pin 60 pocketed in a bearing 61 and urged against a projection 62 on the pawl by means of a spring 63. As the arm 30 rises the sector 50 moves upwardly therewith and the ratchet-teeth 55 on its side are successively engaged by the end of the pawl 56 to prevent retrogressive movement of the arm. The sector 50 is also engaged by a friction-dog 65 which is spring pressed against its forward curved face; this dog 65 also cooperating with suitable stopping-mechanism to arrest the operation of the machine when the winding of the cop or cone is completed. These latter elements form the subject-matter of a separate application and are therefore not herein shown or described in detail. A screw 67 screwed through a lug 68 on the arm 30 is adapted to strike against the top of the extension 43 of the bracket 34 to serve as a stop when the cone-holder is carried down against the drive-roll 15; the screw being adjustable to provide for cone-holders of different sizes.

Having now described the construction and arrangement of the various parts of the improved winding machine its method of operation will next be explained. To prepare the machine for winding the dog 56 is released from the ratchet on the sector 50 and the arm 30 lowered into position with the cone-holder 20, or the cop-tube carried thereby, resting against the periphery of the drive-roll 15, see Figs. 1 and 3. As the cone-holder 20 is brought down into contact with the drive-roll 15 the follower roller 47 slides down to the bottom of the inclined groove or guideway 45 in the cam-track 40. The purpose of the adjusting-means for the cam-track 40 is to provide that the track may be set in proper relation to the cone-holder 20 to insure that the latter will bear evenly along the whole length of the drive-roll 15 as shown in Fig. 3; it being understood that when cone-holders of different dimension or taper are employed on the machine the relation of the cam-track must be changed somewhat. That is to say, in setting the machine for operation the arm 38 is first released from its clamping means so that when the cone-holder 20 is properly placed to rest on the periphery of the drive-roll 15 the cam-track 40 may be adjusted in position with the roll engaging its groove 45 without any tendency for the cam to tilt or tip the cone-holder to remove it from a full contact with the surface of the drive-roll.

With the parts set in the proper relation

as above explained the machine is ready for operation, it being understood that the shafts 4 and 13 are driven from any suitable source of power to rotate the cam 7 to traverse the thread-guide 10, and to drive the roll 15 to rotate the cone-holder 20. The yarn y leads through the slot 16 in the thread-guide 10 and as the latter is reciprocated through the engagement of its roll 8 with the groove 7 in the cam 5 the yarn y will be traversed back and forth on the cone-holder 20 to deposit it in helical coils crossing each other at intervals between the ends of the cone-holder. In U. S. patent 1,588,918, granted June 15, 1926, it is explained that the two grooves in the traverse-cam are of different pitch or lead to provide for regulating the traverse of the thread-guide in accordance with the type of package being wound; one groove being operative on the guide when the machine is employed for winding cones and the other groove being used when the machine is adjusted for winding cylindrical packages. The present invention is concerned only with the winding of conical packages and the groove 7 in the cam 5 is plotted with a progressively changing pitch or lead for the purpose of accelerating the speed of the thread-guide as it traverses toward the smaller end of the cone and correspondingly retarding its speed as it moves toward the base of the cone. The object of this arrangement, as noted in the patent previously referred to, is to cause the yarn to be laid on the cone-holder with the coils or helices having an increased pitch or lead toward the apex end of the cone as compared with their disposition at the base end thereof. This results in the yarn building up faster at the base of the cone than toward its apex end so that the taper on the surface of the package gradually increases from start to finish of the winding. This increase in the taper takes place as the cone-holder 20 recedes from the drive-roll 15, and to provide that the surface of the winding, notwithstanding its change in taper or conicity, be maintained constantly in full contact with the periphery of the drive-roll 15 it is necessary that the cone-holder be tilted to progressively increase the angle of inclination of its axis with respect to the drive-roll as the holder recedes from the roll. As the cone-holder 20 is forced upwardly from the drive-roll 15 by the increasing mass of the cone being wound the arm 30 swings upwardly about its pivot 35, and meanwhile the bearing-member 22 is rocked on its pivot 29 under the action of the cam-track 40. That is to say, as the cone-holder 20 rises away from the drive-roll 15 the roller 47 on the arm 46 slides through the cam-groove 45, and since the groove is inclined at an angle to the normal vertical path of the arm 30 it will act on the roller 47 and through the arm 46 to gradually rock the bearing-member 22 on the stud 29, see Figs. 3 and 4. The inclination of the cam-groove 45 causes the arm 46 to be rocked toward the right as viewed in Figs. 3 and 4, and consequently the cone-holder 20 will be tilted downwardly at its nose with its axis assuming a greater degree of inclination to the axis of the drive-roll 15 as the holder recedes therefrom. Moreover, since the axis of the cone-holder 20 is offset or displaced below the pivotal axis on which the bearing-member 22 swings the tilting of the cone-holder 20 will also cause it to be shifted bodily in the longitudinal direction of its base. Stated briefly, the tilting of the cone-holder on an axis out of line with its own axis causes the holder to be displaced bodily to the right longitudinally of the drive-roll 15 during the movement of the holder away from the roll. Now since the path of traverse of the thread-guide 10 is constant with respect to the drive-roll 15 the layers of yarn deposited on the cone-holder will be gradually and progressively stepped forward in the direction of the apex of the cone as indicated by the dot-and-dash lines in Fig. 4. In other words, the yarn will be built up in a mass which not only has a gradually increasing taper on its peripheral surface, but with the layers displaced longitudinally of the axis of the cone-holder so that the base of the cone assumes a convex form while its apex end is correspondingly concaved. Such a form of cone having an increasing taper on its surface and concavo-convex ends has certain advantages as well known in the winding art. First, it provides for a freer delivery of the yarn from the surface of the cone in unwinding it; and, second, the convexity of the base tends to prevent overruns or loose coils of yarn at this end of the cone. That is to say, where the yarn-coils reverse at the base end of the cone they are supported in more stable relation and restrained from slipping out of place, thus preventing overruns, "cobwebs" or loose loops which would be apt to impede the free delivery of the yarn when it is drawn off over the apex end of the cone.

As the cone-holder 20 rises from the drive-roll 15 retrogressive movement is prevented by the action of the dog or pawl 56 on the ratchet-sector 50. The roller 47 is therefore prevented from sliding back in the cam-groove 45 so that there will be no tendency for the cone-holder 20 to vibrate or oscillate, its movement away from the drive-roll 15 being accomplished with a smooth and even action and its angle of inclination to the roll controlled positively. The double faces of the cam-groove 45 being constantly in engagement with the follower roller 47 prevent play or lost motion between the parts,

so that the cone-holder has no tendency to jump or rock during its rotation under the driving action of the roll 15. In other words, the control of the tilting action is made positive to such a degree that there is no undue vibration or jumping action of the cone on the drive-roll and therefore the yarn is disposed in smooth level layers to form a uniformly dense, compact package of true contour in accordance with the prescribed degree of taper on its surface and convexity at the base.

My present invention, while similar in some respects to the machine of the patent hereinbefore referred to embodies improvements thereover in the construction and method of operation of the parts. As one particular feature of improvement the cone-builder mechanism is reduced to the simplest and most direct form by mounting the cone-holder on the swinging arm 30. The cam-track or guide 40 which controls the tilting action of the cone is of relatively short length and its control of the cone-holder through the roller 47, arm 46 and bearing-member 22 is made more direct, resulting in a close coupling which eliminates backlash and lost motion and therefore insures a more positive action for the purpose described. Furthermore, the builder-motion is compacted and condensed within a minimum space to reduce the dimensions of the whole machine. The simplicity of the mechanism also makes for greater ease of operation, and insures against its becoming deranged or getting out of order.

While I have herein shown and described a preferred form of construction of the device it is to be understood that various modifications may be made therein without departing from the spirit or scope of the invention. Therefore, without limiting myself in this respect I claim:

1. In a winding machine, the combination of a cone-holder, a drive-roll for rotating the cone wound on the holder, means for traversing the yarn on the holder, a swinging arm, means for rockably supporting the cone-holder on the arm to adapt it to tilt at an angle to the drive-roll, and means for tilting the cone-holder on the arm while positively restraining it from rocking or vibrating as it swings upwardly from the drive roll to control its angle of inclination with respect thereto whereby to regulate the taper on the surface of the cone being wound.

2. In a winding machine, the combination of a winding-mandrel, a drive-roll for rotating the package wound on the mandrel, means for traversing the yarn longitudinally of the mandrel, a swinging arm, a bearing-member rockable on said arm and connected to support the winding-mandrel, and means for rocking said bearing-member to tilt the mandrel with respect to the drive-

roll while positively restraining it from jumping or vibrating as it recedes from the drive roll with the swinging movement of the arm.

3. In a winding machine, the combination of a hinged arm, a bearing-member pivoted to rock on the arm, a cone-holder rotatably carried by the bearing-member, means for traversing the yarn on the cone-holder, a drive-roll for rotating the cone wound on the holder, an inclined double-sided cam-track, and means on the bearing-member engaging the opposite sides of the cam-track to positively tilt the cone-holder with respect to the drive-roll during its receding movement therefrom.

4. In a winding machine, the combination of a swinging arm, a cone-holder rotatably mounted on said arm and adapted to rock with respect thereto, means to traverse the yarn on the cone-holder, a drive-roll for rotating the cone wound on the holder, a fixed double-sided cam-track, and a follower engaging the opposite sides of the track and acting to positively tilt the cone-holder on its arm during the swinging movement of the latter as the holder recedes from the drive-roll.

5. In a winding machine, the combination of a rotating drive-roll, an arm pivoted on an axis parallel with that of the drive-roll, a cone-holder rotatably supported from said arm and pivoted to rock on an axis at right-angles to the axis of the drive-roll, a double-sided cam-track, and a follower engaging the opposite sides of said track and acting to positively rock the cone-holder on the arm to tilt the latter with respect to the drive-roll during its receding movement therefrom.

6. In a winding machine, the combination of a drive-roll, an arm hinged on an axis parallel with that of the drive-roll, a rotatable cone-holder pivoted on said arm to rock on an axis offset from its own axis, a double-sided cam-track, and a follower travelable on the opposite sides of said track during the swinging movement of the arm to positively tilt the cone-holder with respect to the drive-roll while bodily displacing the holder longitudinally of the drive-roll.

7. In a winding machine, the combination of a drive-roll, an arm pivoted to swing on an axis parallel with that of the drive-roll, a bearing-member hinged to said arm to rock on an axis at right-angles to that of the drive-roll, a cone-holder rotatably mounted on said bearing-member with its axis offset from the pivotal axis thereof, a fixed double-sided cam-track, and a follower carried by the bearing-member and engaging the opposite sides of the cam-track to cause it to positively tilt the cone-holder as the latter recedes from the drive-roll.

8. In a winding machine, the combination of a drive-roll, an arm pivoted to swing on

100

105

110

115

120

125

130

- an axis parallel with that of the drive-roll, a bearing-member pivoted to the arm to adapt it to rock on an axis at right-angles to that of the drive-roll, a cone-holder rotatably mounted on said bearing-member, an arcuate track arranged concentric with the axis of the swinging arm and inclined at an angle to the vertical, and a follower on the bearing-member engaging said track to cause it to tilt the cone-holder as it moves with the arm during its recession from the drive-roll.
9. In a winding machine, the combination of a drive-roll, an arm pivoted to swing on an axis parallel with that of the drive-roll, a rotatable cone-holder rockably mounted on the arm, an arcuate track pivoted to adapt it for adjustment about the axis of the swinging arm, means for fixedly securing said track in adjusted position with relation to the arm, and a follower engaging the track and adapted to tilt the cone-holder with respect to the drive-roll during its receding movement therefrom.
10. In a winding machine, the combination of a drive-roll, a traversing thread, a guide, a support, an arm hinged to said support to adapt it to swing on an axis parallel with that of the drive-roll, said arm formed with a bearing-stud extending at right-angles to its pivotal axis, a bearing-member pivoted on said stud, a cone-holder rotatably mounted on said bearing-member below its pivotal axis, an inclined trackway, and a follower on the bearing-member engaging the track and acting to tilt the cone-holder as the latter moves with the arm during its recession from the drive-roll. 25
